UNITED STATES PATENT OFFICE.

OTTO T. POST, OF CHARLOTTENBURG, GERMANY, ASSIGNOR TO ALLGEMEINE ELEKTRICITÄTS-GESELLSCHAFT, OF BERLIN, GERMANY.

POWER-PLANT INSTALLATION.

Application filed July 7, 1924. Serial No. 724,735.

To all whom it may concern:

Be it known that I, Otto T. Post, a citizen of Germany, residing at Charlottenburg, Germany, have invented certain new and useful Improvements in Power-Plant Installations, of which the following is a specification.

The present invention relates to power plant installations employing both high pressure and low pressure elastic fluid prime movers, and more particularly it relates to such power plant installations wherein the exhaust of one or more of the high pressure prime movers is utilized as motive fluid in one or more of the low pressure prime movers.

The object of the present invention is to provide an improved arrangement and means, in a power plant installation of the above type for more advantageously utilizing in a low pressure prime mover the exhaust elastic fluid from a high pressure prime mover, while rendering the two prime movers mutually independent in operation.

In similar power plant installations heretofore, the mutual dependency of two prime movers, which operate in series relation on a common stream of motive fluid, has been avoided to a limited extent by providing an auxiliary supply source of suitable pressure, such as a separate boiler directly connected with the low pressure prime mover, along with the exhaust conduit of the high pressure prime mover, so that with a decrease in the supply from the high pressure prime mover, the requirements of the lower pressure prime mover could be met by drawing upon the auxiliary source.

This arrangement does not, however, provide for utilizing increases in the amount of motive fluid supplied by the high pressure prime mover over that required by the low pressure prime mover. Furthermore, this arrangement depends upon the heat exchange between the superheated elastic fluid from the auxiliary supply source and the low temperature exhaust elastic fluid to superheat the latter as the two fluids pass through the low pressure prime mover. This is obviously less efficient as a method for superheating the exhaust elastic fluid than the well known method of superheating within a gas heated superheater interposed between the prime movers.

In accordance with the present invention,

means are provided not only for rendering the low pressure prime mover independently operable but also for rendering the high pressure prime mover independently operable, so that either prime mover may carry a variable load without influencing the operation of the other. In addition, means are provided for obtaining the desired superheating of the exhaust from the high pressure prime mover before it is utilized in the low pressure prime mover under all conditions of operation.

The invention is herein described and illustrated, by way of example, in connection with a steam turbine power plant installation embodying one high pressure turbine and one low pressure turbine and, for a consideration of what is believed to be novel and the invention, attention is now directed to the accompanying drawing, description thereof and the appended claims.

In the drawing, the figure is a diagrammatical representation, partly in section, of a steam turbine power plant installation embodying the invention.

Referring to the drawing, 2 is a high pressure steam turbine and 3 is a low pressure steam turbine connected together by a shaft coupling 4. Mounted on an extension 5 of the shaft of the low pressure turbine is an electric generator 6 which furnishes a common load for the two turbines, although it should be understood that this is merely by way of example and that the turbines may, if desired, be connected each to a separate and different generator or other form of load.

The high pressure turbine 2 is provided with an inlet at 7 and an exhaust outlet at 8. The inlet 7 is connected with a steam chamber 9 of a high pressure boiler 10 by a high pressure supply conduit 11 and the exhaust outlet 8 is connected with a steam chamber 12 of a low pressure boiler 13 by an exhaust conduit 14.

The low pressure turbine 3 is provided with an inlet at 15 and an exhaust outlet at 16. The inlet 15 is connected with the steam chamber 12 of the low pressure boiler 13 by a low pressure supply conduit 17. The exhaust outlet 16 may be connected to any suitable receiving or condensing means (not shown). Between the turbine inlet 15 and the steam chamber 12, a superheater 18 is inserted in the supply conduit 17. The su-

perheater is shown in the present example as being a simple vertical coil formed in the conduit 17, although it may be of any suitable form. As will be readily appreciated, the arrangement is such that the low pressure boiler 13 and the superheater 18 are inserted in the connection between the exhaust outlet 8 of the high pressure turbine and the inlet 15 of the low pressure turbine.

The boilers illustrated are substantially similar in construction and represent any suitable high and low pressure boilers. They are of the horizontal drum type having a fire box or combustion chamber 19 at one end and a fire tube 20 extending therefrom longitudinally of the boiler. The fire box is provided with a grate 21 on which the fuel, indicated at 22, is burned. The space above the grate communicates with the fire tube and is provided with a fuel door 23 at the front of the boiler. The space below the grate is provided with an air inlet opening 24 and a draft controlling damper 25 at the front of the boiler and is separated from the fire tube 20 by a wall 26 which supports the inner end of the grate.

The fire box and fire tube are located below the water level, which is indicated at 27, and are thus in a position to effectively heat and vaporize the water. The water level is such that a liberal vapor or steam storage space 28 is provided above it, especially in the low pressure boiler 13 for reasons which will be hereinafter explained. The steam chambers 9 and 12 hereinbefore mentioned are in communication with and form part of their respective storage spaces 28.

The boilers are mounted in a masonry setting or foundation structure 29, of which the floor level is indicated at 30. Below this level a flue passage 31 is formed in said structure for receiving the products of combustion from the fire tubes of the boilers, a vertical extension passage 32 forming a connection with the fire tube of the high pressure boiler 10, and a similar vertical extension passage 33 forming a connection with the fire tube of the low pressure boiler 13.

The extension passage 32 is controlled by a damper plate 34 which is arranged to slide vertically, in a slot 35 in the floor 30 of the foundation structure, into and out of the flue passage 31. It is shown in the normal or raised position, providing free communication between the fire tube of the high pressure boiler and the flue passage 31.

The extension passage 33 is controlled by a damper plate 36 pivoted at 37 to swing vertically over an opening 38 between said extension passage and the flue passage. This damper plate is gravity closed and is raised to the normal open position shown, by a pull-chain 39 which is connected at its outer edge and passes vertically upward there-

from through an opening 40 in the foundation structure to an idler wheel 41. From the idler wheel it may be extended to any desired control point (not shown).

The fire tube 20 of the low pressure boiler 70 is provided with a by-pass 42 which leads from a point adjacent the fire box 19 directly into the flue passage 31. The by-pass is provided with a sliding damper 43 which lies at right angles thereto in a slot 44 in the 75 foundation structure. The damper is movable into or out of the normal closed position shown, by a handle 45 which protrudes beneath the boiler front.

At the rear of the low pressure boiler 13, a chamber 46 is formed in the foundation structure as an enlargement and continuation of the flue passage 31. The superheater 18 is located within this chamber on a perforated support 47. A vertical baffle wall 85 48, which joins the bottom wall and terminates short of the top wall of the chamber, is located closely adjacent to the superheater and serves to direct the flue gases upwardly through the perforated support and about 90 the superheater. The support 47 and baffle wall 48 are formed integral with the masonry foundation. At the opposite side of the baffle wall, an outlet opening 49 is provided in the outer wall of the chamber from 95 which the flue gases may pass to atmosphere through any suitable means such as the usual and well known stack or chimney (not shown). The normal direction of flow of 100 the flue gases from the fire boxes 19 to the outlet 49 is indicated by suitably placed arrows.

The normal operation of the installation is as follows:—Assuming that the steam requirement of the low pressure turbine is greater than that of the high pressure turbine, that is, that the high pressure turbine is supplying exhaust steam at a lower rate than is required by the low pressure turbine, and that both boilers are in operation with damper plates 34 and 36 raised and damper 43 closed, all as shown, high pressure steam is supplied to the high pressure turbine 2 from the high pressure boiler 10 through the high pressure supply conduit 11. After 105 doing work in the turbine 2, the exhaust steam is conducted by the exhaust conduit 14 to the steam chamber 12 of the low pressure boiler 13 where it is mixed with the low pressure steam in the storage space 28 of said low pressure boiler. The exhaust steam from the high pressure turbine is partially reheated in mixing with the steam generated in the low pressure boiler and passes along with the generated steam by 110 way of the low pressure supply conduit 17 through the superheater 18 to the low pressure turbine 3 where it supplements said generated steam in doing further work. The 115 arrangement is such that the exhaust steam 120

from the high pressure turbine is superheated well above the saturation point before being utilized in the low pressure turbine, the superheating being accomplished for the most part in the superheater 18 which is located in a position to be traversed by the flue gases from both boilers.

The low pressure boiler supplements the exhaust from the high pressure turbine in providing the low pressure turbine with the required amount of steam, thus rendering the turbines mutually independent under this condition of operation.

Assuming now that the steam requirement of the low pressure turbine becomes equal to or less than that of the high pressure turbine. The low pressure boiler becomes a storage tank, the exhaust steam from the high pressure turbine being stored in the steam storage space 28. Under this condition of operation if continuous, the generation of steam in the low pressure boiler may be checked by opening the sliding damper 43 and closing the damper plate 36 over opening 38 so that the fire tube 20 of the low pressure boiler is cut off and the flue gases discharged through the by-pass 42. The heat in said flue gases is then utilized only in the superheater 18.

The steam storage space 28 of the low pressure boiler is designed to be relatively large so that its capacity will be sufficient to meet the usual operating differences between the quantity of steam supplied by the high pressure turbine and the demand for steam by the low pressure turbine. The low pressure boiler thus forms between the high pressure turbine and the low pressure turbine, a flexible coupling or storage means in which additional low pressure steam may be generated when required.

In case the operating conditions are such that the steam requirement of the low pressure turbine is so low that the low pressure boiler is not required for the generation of steam, the fire may be withdrawn and both dampers 43 and 36 may be closed, thus isolating the boiler from the flue passage 31. Under this condition of operation, which may be considered unusual, the low pressure boiler operates as a storage tank as before, and the superheater is supplied with heating gases only by the high pressure boiler.

It should be understood that the damper plate 36 of the low pressure boiler is used not only in the closed or open positions as hereinbefore described in connection with the operation, but also in various intermediate positions to control the combustion rate in conjunction with the draft controlling damper 25 of said low pressure boiler, as is well understood in connection with the operation of any boiler. Likewise the sliding damper 43 may be moved to such positions that various quantities of the combus-

tion gas may be by-passed directly to the flue to control the generation of steam in said low pressure boiler. In connection with the operation of the high pressure boiler 10, the combustion is controlled by the damper 70 plate 34 and the draft door 25.

To further illustrate the operating flexibility of the arrangement as provided in accordance with the invention, a condition of operation will be assumed under which it is desirable or necessary to remove the high pressure boiler 10 and high pressure turbine 2 from service whereby, in the present example, the low pressure turbine 2 alone will drive the generator 6.

Under this condition of operation the fire is withdrawn from the high pressure boiler 2 and damper plate 34 is lowered to cut off said boiler from the flue passage 31. The high pressure turbine 2 may remain connected with the high and low pressure boilers as shown, or be cut off therefrom by any desired means such as valves. In the present example, the high pressure turbine 2 and boiler 10 are merely subjected throughout to the low pressure of the low pressure boiler 13 and as no outlet is provided in the high pressure boiler 10, or high pressure supply conduit 11, no flow of steam will take place in said high pressure turbine.

The low pressure boiler 13 then supplies the low pressure turbine 3 with steam and the superheater 18 with heating flue gases as if it were a complete installation entirely separate from the high pressure turbine and boiler. The damper plate 36 and draft door 25 are opened in accordance with the demands upon the boiler to provide the desired draft conditions and the damper 43 is moved to close the by-pass 42.

From the foregoing description of the present embodiment of the invention, it will be seen that a power plant installation is provided in which a lower pressure prime mover is arranged to receive the exhaust elastic fluid from a higher pressure prime mover through the intermediary of an auxiliary elastic fluid supply means which renders the installation flexible in operation and the prime movers mutually independent, in conjunction with means for superheating the supply to the low pressure prime mover under all conditions of operation. It will be readily appreciated by one skilled in the art that within the scope of the invention an additional lower pressure turbine may, if deemed advisable in certain installations, be connected with the exhaust outlet 16 of the low pressure turbine through means duplicating that which connects the present low pressure turbine with the exhaust outlet of the high pressure turbine.

It should be understood that other high pressure turbines and boilers may be connected in parallel with the high pres-

sure turbine and boiler shown and that low pressure turbine and boiler likewise represent any desired number of low pressure turbines and boilers connected in parallel with them, and it should be understood further that while the invention has been herein described in connection with an illustration representing what is now considered to be the best embodiment thereof, said invention may be carried out by other means.

What I claim as new and desire to secure by Letters Patent of the United States, is:—

1. In a power plant installation, the combination with a high pressure and a low pressure prime mover, of separate elastic fluid generators for said prime movers, means for conducting the exhaust elastic fluid from the high pressure prime mover to the elastic fluid generator of the low pressure prime mover, said generator having a relatively large elastic fluid storage capacity, and a superheater which lies in the path of combustion gases from the generators connected between the said low pressure generator and the low pressure prime mover.

2. In a power plant installation having an initial higher pressure prime mover and a lower pressure elastic fluid prime mover, the lower pressure prime mover being connected to receive the exhaust elastic fluid from the higher pressure prime mover, the combination of an elastic fluid generator connected with the initial higher pressure prime mover, and means interposed in the connection between the higher and lower pressure prime movers for rendering said prime movers mutually independent in operation, said means comprising a separate elastic fluid generator of relatively large storage capacity and a superheater which lies in the path of combustion gases from the generators.

3. In a power plant installation, the combination of a high pressure elastic fluid prime mover, a high pressure boiler connected therewith, a low pressure elastic fluid prime mover, a low pressure boiler connected therewith, said low pressure boiler having a relatively large elastic fluid storage capacity, a conduit connection between the exhaust outlet of the high pressure prime mover and the low pressure boiler, a superheater interposed in the connection between the low pressure prime mover and the low pressure boiler, a common flue passage for the high and low pressure boilers in which said superheater is located, and means for connecting and disconnecting either of said boilers and the flue passage.

4. In a power plant installation, the combination of a high pressure elastic fluid turbine, a high pressure boiler connected therewith, a low pressure elastic fluid turbine, a low pressure boiler connected therewith, said low pressure boiler having a relatively large elastic fluid storage capacity, a superheater connected between the low pressure boiler and the low pressure turbine, a conduit connection between the exhaust outlet of the high pressure turbine and the low pressure boiler, and means for conducting combustion gases from the high and low pressure boilers through said superheater, said means including a common flue passage for the boilers in which the superheater is located, dampers for isolating either or both of said boilers from the flue passage, a by-pass in the low pressure boiler, connecting the flue passage directly with a point within said boiler adjacent its combustion chamber, and a damper controlling said by-pass.

In witness whereof, I have hereunto set my hand this 26th day of June, 1924.

OTTO T. POST.
